UNITED STATES PATENT OFFICE.

WILLIAM PEARCE, OF PLANTSVILLE, ASSIGNOR TO HIMSELF, AND M. N. WOODRUFF AND N. A. BARNES, BOTH OF SOUTHBINGHAM, CONN.

METHOD OF FORGING OX-SHOES.

SPECIFICATION forming part of Letters Patent No. 314,191, dated March 17, 1885.

Application filed February 16, 1885. (No model.)

To all whom it may concern:

Be it known that I, WILLIAM PEARCE, of Plantsville, in the county of Hartford, and in the State of Connecticut, have invented certain new and useful Improvements in the Manufacture of Ox-Shoes; and I do hereby declare that the following is a full, clear, and exact description thereof, reference being had to the accompanying drawings, in which—

10 Figure 1 is a perspective view of the upper and lower dies used by me in the forging of ox-shoes having parallel calks. Fig. 2 is a like view of said lower die arranged for forging the ordinary form of shoe. Fig. 3 is a perspective 15 view of a blank and a completed shoe as left by the dies shown in Fig. 1. Fig. 4 is a like view of the same as left by the dies shown in Fig. 2. Fig. 5 is a section of the dies through the longitudinal axis of one of the recesses, 20 said dies being closed together upon a bar of iron; and Figs. 6 and 7 are respectively perspective views of the trimming-dies shown in connection with the dies shown in Figs. 1 and 2.

Letters of like name and kind refer to like 25 parts in each of the figures.

The object of my invention is to enable ox-shoes to be quickly and easily produced from a straight bar by means of dies, to which end said invention consists in the method employed 30 for forging ox-shoes from a straight bar of iron, substantially as and for the purpose hereinafter shown.

In the carrying into effect of my invention I employ two forging-dies, A and B, which 35 for convenience are formed within one block of metal and are arranged side by side; but may, if desired, be formed separately. The first of said dies, A, has the general size and shape of the desired shoe C, and is provided 40 with a small half-round rib, a, that partly forms the nail-groove c of said shoe, while said die B has the exact size and shape of the finished shoe, and is provided with a rib, b, that has a Δ shape in cross-section and is adapted 45 to complete said nail-groove c.

In practice a straight bar of iron is heated and placed over the die A in substantially a line with the transverse centers of the calk-recesses a' and a'', in which position said bar is subjected to the action of an upper plain-faced die, D, and caused to fill the cavities of said die A.

The partially-forged shoe C is now placed over the second die, B, and by means of one or more blows from said upper die is forced into the

former and given the exact shape required. 55 As the metal under the action of the upper die must flow outward and downward in the preliminary die, A, so as to fill the recess at such point, and from the outer thickest portion of the shoe C, it is necessary that the rib a 60 should be low and transversely rounded, so as not to be an obstruction to the movement of the heated metal or to cause at such point a cold sheet.

In order that the shoes may be forged directly from a bar without first cutting the same into lengths, the upper die, D, has but slightly greater length than is necessary to enable it to cover the recesses in the dies A and B, and in use its ends cut into said bar and nearly 70 sever the metal, leaving at each end of the shoe C a sprue, c', that serves to connect said shoe with the previously-forged shoe in front, and with said bar at its rear, and enables a number to be forged at one heat from said bar 75 without separation. While the corners of said die D are preferably left square, they may, if desired, be rounded or formed at any angle.

After the shoes C have passed through the finishing-die B each is placed over a female 80 trimming-die, E, that has an opening, e, corresponding to the outline of the completed shoe, and is then operated upon by an upper male die, F, which forces said shoe through said opening and removes all surplus metal 85 from its edges.

The dies shown and described are not herein claimed, as they form the subject of a separate application for patent.

Having thus fully set forth the nature and 90 merits of my invention, what I claim is—

As an improvement in the forging of ox-shoes, the hereinbefore-described method, consisting in the placing of a straight bar of heated metal having less width than the finished 95 shoe longitudinally over the intaglio of a die, and then causing the metal to fill said die by blows from a plain-faced upper die which has but slightly greater length than the length of said intaglio, substantially as specified.

In testimony that I claim the foregoing I have hereunto set my hand this 10th day of February, A. D. 1885.

WILLIAM PEARCE.
